UNITED STATES PATENT OFFICE.

LILLIE A. MILNE, OF FRESNO, CALIFORNIA.

PRESERVATIVE FOR LEATHER AND LEATHER SUBSTITUTES.

1,307,059.

Specification of Letters Patent. Patented June 17, 1919.

No Drawing.

Application filed September 25, 1918. Serial No. 255,710.

To all whom it may concern:

Be it known that I, LILLIE A. MILNE, a citizen of the United States, and a resident of the city of Fresno, county of Fresno, and State of California, have invented a new and useful Preservative for Leather and Leather Substitutes, of which the following is a specification.

My invention relates to a composition of matter which is to be applied to the surface of leather or leather substitutes with a brush or similar means, the objects and purposes being to fill the pores of the leather, make it pliable, tough and water proof, thus prolonging the life of the leather and giving it better wearing qualities.

My composition consists of the following ingredients combined approximately in the proportions stated, to-wit:

20 Seventy-five parts of gas tar, being the residue of crude mineral oil after the manufacture of illuminating gas therefrom, and twenty-five parts gum copal varnish. These ingredients are to be thoroughly mixed by 25 agitation. In using the above composition the leather or leather substitute should be thoroughly cleansed and the composition placed thereon with a brush or cloth, or any other suitable manner so it is rubbed thoroughly in the pores.

This composition is especially desirable for the preservation of leather used in making shoes and shoe soles, and for shoes already made, and for leather subject to hard and rough usage. Its application to leather 35 makes it practically water proof as well as soft, pliable and tough, and lengthens its life.

I claim:

1. The herein described composition of 40 matter consisting of seventy-five parts of crude mineral oil gas tar, and twenty-five parts of gum copal varnish, thoroughly mixed, substantially as described and for the purposes set forth.

2. The herein described composition of 45 matter for preserving leather consisting of approximately seventy-five parts of gas tar, being the residue of crude mineral oil after the manufacture of illuminating gas therefrom, and approximately twenty-five parts of gum varnish thoroughly mixed substantially as described.

LILLIE A. MILNE.
